UNITED STATES PATENT OFFICE.

CLARENCE P. RUMFELT, OF OAKLAND, CALIFORNIA.

OIL-CAN.

1,056,945.

Specification of Letters Patent. Patented Mar. 25, 1913.

Application filed September 6, 1912. Serial No. 718,811.

To all whom it may concern:

Be it known that I, CLARENCE P. RUMFELT, a citizen of the United States, residing at Oakland, in the county of Alameda and State of California, have invented certain new and useful Improvements in Oil-Cans; and I do declare the following to be a full, clear, and exact description of the invention, such as will enable others skilled 10 in the art to which it appertains to make and use the same.

This invention relates to dispensing cans, and more especially to the nozzles thereof which have automatic cut-offs; and the object of the same is to provide a peculiar form 15 of automatic closure for the extremity of the nozzle, and means for opening it by the tip of the finger of that hand which holds the oil can. These and other objects are carried out by constructing the can and its 20 parts in the following manner, as shown in the drawings wherein—

Figure 1 is a side elevation of this improved oil can, and Fig. 2 a similar elevation at right angles thereto. Fig. 3 is an enlarged detail of the spout, showing how the pad which normally closes its outlet can be pressed aside by the finger. Figs. 4 and 5 are sectional views on the lines 4—4 and 30 5—5 of Fig. 1. Fig. 6 is a perspective view of the pad removed from the oil can, and Figs. 7 and 8 are bottom plan views of the oil can and pad plate, showing the latter in Fig. 7 as being put in place, and in Fig. 8 35 after it has been turned to hold the same in place.

The body 1 of the can is by preference made of tin or sheet metal with a chine around its lower end which is notched as at 40 2 at intervals so as to leave tongues 3, some of which are bent inward.

The numeral 4 designates a circular or nearly circular plate to which is attached a sheep skin pad 5, and when this plate is 45 brought into proper position it can be passed into the space bounded by the tongues 3 and turned so as to be locked therein. Thereafter the body of the oil can carries this pad on its lower end, and when tools and pieces 50 of machinery are oiled to remove rust the pad can be used for rubbing rusty parts, or when they are oiled too copiously the pad can be removed for wiping it off. When the pad is not desired, it is turned partly so that 55 the flattened sides 6 of the metal plate come opposite the tongues 3 which are bent in-

ward and the entire pad and its supporting plate can be detached.

At one point the body of the oil can carries a steel scraping plate 7, by means of 60 which dirt, tar, pitch, rosin, and other foreign substances can be scraped off of tools and parts of machinery, or rust can be loosened before or after it is oiled.

The top of the body of this can is formed 65 by preference in the shape of a dome 9 having a threaded nipple 10, and engaging the latter is a threaded inner end of the spout 11 which tapers throughout its length as shown and is not otherwise of special construction.

All parts hereinbefore described save the 75 parts 5 are by preference of metal, and the whole is constructed much like other oil cans now on the market.

The numeral 12 designates a spring secured as at 13 to one side of the nozzle or spout 11, carried out along the same and making a transverse bend 14 where it extends across the back of the spout about the 80 mid-length of the latter, and thence carried along other side of the same to its smaller end and slightly beyond its extremity where it is bent into a lateral foot 15, slightly flattened and extending across the extremity of the 85 spout which is here beveled off on its front or lower side as at 16; and to this foot is secured a small pad 17 of leather and by means of a fine wire loop 18. The normal tendency and tension of the spring is sufficient to throw the foot toward the tip of the 90 spout 11 so that the pad 17 will rest on the beveled extremity as at 16; but when this oil can is to be used for oiling anything, it is inverted and the outer stretch of the 95 spring 12 is pressed against the edge of the oil hole into which the lubricant is to be injected so that the foot is sprung away from the beveled extremity of the nozzle, and oil flows out the latter. If the oil hole is not 100 sufficiently large, it is quite possible for the finger of the operator to be pressed upon some portion of the spring 12, as seen in Fig. 3. The spring is extremely light and bends easily under pressure, its only function being to support the leather pad 17 and cause the same to rest against the extremity of the spout. I preferably employ leather for this purpose, because the flowing of lubricating oil through the spout will keep it soft; 105 but if the operator should endeavor to use some other liquid, as for instance gasolene,

in this oil can, he will soon find it will harden the leather pad and crack and destroy it. It then becomes necessary to remove the pad as by loosening the wire 18, 5 replacing the pad by another and tightening the wire. The transverse bend 14 in the spring is so disposed with reference to the two arms thereof that when this bend is pressed against the spout 11, the foot 15 10 thereof is pressed away from the extremity 16, and the bend therefore acts as a stop to prevent the free end of the spring from being pressed too far out of position.

All parts excepting the pads are prefer- 15 ably of metal, and of the desired proportions consistent with the use to which this device is to be put.

What is claimed as new is:

An oil can having the tip of its nozzle

beveled off; combined with a light spring 20 secured to the nozzle near its base, extending thence along one side of the nozzle, carried transversely over the same at about its midlength, extending thence along the other side of the nozzle, and having a flattened 25 foot at its outer end carrying a pad normally thrown over the beveled tip of the nozzle by the spring but capable of being pressed away from the same by the operator, for the purpose set forth.

In testimony whereof I have hereunto set my hand in presence of two subscribing witnesses.

CLARENCE P. RUMFELT.
